UNITED STATES PATENT OFFICE

LOUIS H. WELLENSIEK, OF HOUSTON, TEXAS, ASSIGNOR TO HUGHES TOOL COMPANY,
OF HOUSTON, TEXAS, A CORPORATION OF TEXAS

CORE BIT CONSTRUCTION

Application filed March 24, 1931. Serial No. 524,810.

My invention relates to core drills such as are employed in obtaining the samples of formation in deep well drilling for oil, gas or sulphur, and the like. It pertains particularly to hard formation core drills having rolling cutters thereon.

It is an object of the invention to provide a roller core drill being so constructed that the core-engaging dogs may be mounted closely adjacent to the lower end thereof.

I also include as an improvement a particular construction of core-engaging dogs which are easily operated and not liable to stick in position in the head and fail to operate.

I also desire to provide an effective and positive means of moving the dogs into core-engaging position.

It is a further object to provide means to effectively lubricate the drill head construction so that the parts may easily move when it is desired to operate the core catcher.

I have as a further object to provide a drill head construction, whereby the cutter head may be easily connected and disconnected from the cutter body when desired.

In the drawings herewith Fig. 1 is a central longitudinal section through a core drill and its supporting body, the construction of which embodies a preferred form of my invention.

Fig. 2 is a transverse section on the plane 2-2 of Fig. 1.

Fig. 3 is a similar section on the plane 3-3 of Fig. 1.

Fig. 4 is a broken section of a portion of the drill body taken on the plane 4-4 of Fig. 1.

Fig. 5 is a vertical section on an enlarged scale showing the construction of my core-engaging dogs.

Fig. 6 is a similar view showing the core-engaging dogs in operative position.

Fig. 7 is a perspective view of one of the dogs removed.

Fig. 8 is a connecting pin engaging the cutter dogs in the operation of the core catcher.

Fig. 9 is a transverse section on the plane 9-9 of Fig. 1.

In constructing my device I employ an elongated tubular body 10. The lower end of said body is increased somewhat in outer diameter and has a shoulder 11 at the lower end to contact with the upper ends 12 of the cutter supports 13. In the lower end of said body are provided a plurality of cylindrical recesses 14 threaded to receive tubular pins 15 which connect the cutter body with the upper ends of the cutter supports. The upper end of the cutter body 10 is recessed somewhat on its inner side 16 to receive a sleeve 17 acting as a packing sleeve, as will be later described.

The upper end 18 of the cutter body abuts against a shoulder 19 on the drill collar 20. Said drill collar has an upper threaded socket 21 to engage with a tool joint or other coupling member by means of which the drill may be attached to the drill stem. The drill collar telescopes slidably over the upper end of the cutter body 10 and is increased in internal diameter at 22, forming a shoulder 23 thereon to limit the upper movement of a floating ring 24 fitting between the drill collar and the body 10. Said ring has packing rings 25 on its outer surface and on its inner surface it engages with similar rings 25' set in recesses in the outer periphery of the body 10. The lower end of the drill collar engages slidably with the lower end of the cutter body.

The cutter supports 13 are made up of blocks of metal, the upper ends of which are extended inwardly to engage on the upper end of a cutter head 26. Said head is a ring shaped member, the upper end of which is shouldered off to fit against shoulders 27 on the cutter supports. The lower end is beveled outwardly at 28. The outer side of the head 26 is recessed slightly at 29 adjacent each of the cutters to provide a space in which the cutters may move. Each cutter support 13 has a tapered shaft 30 thereon upon which the rotating cutters 31 are mounted. The inner end of each cutter shaft 30 may be welded as shown at 32, to the cutter body. Each support 13 is provided with an opening therein to receive the lower ends 33 of the tubular pins 25. The outer side of each of the

- cutter supports is formed with a mortised recess 35 transversely thereof, and the outer side of each of the tubular pins 15 is recessed to provide a keyway 36 within which the keys 37 may be received.
- 5 Thus in assembling the drill head upon the drill body, the pins 15 will be threaded into the lower end of the drill body, and the drill head will then be moved into position; the recesses in the head receiving the lower ends of the pins 15 and the keys 37 will then be driven into position, wedging the head upwardly against the drill body and locking the same firmly in position. The outer ends of the keys may then be bent over, and the head will then be held against removal in operation.

- 10 The core-engaging dogs are mounted in rectangular shaped blocks 38 which are formed to fit within the spaces between the upper ends of the supporting blocks 13 and at the lower ends thereof and within the recesses 39 in the lower end of the cutter body. This will be understood best from Fig. 1.
- 15 The blocks 38 thus fit partially within the space between the cutter supports and partly in the cutter body, and will assist in taking the thrust due to the torque of the rotating drill during operation.
- 20 The supports 38 for the cutter dogs are welded in position as shown at 40, and when thus secured form an integral part of the said cutter body. Each block is formed with a recess 41 therein, which with reference, particularly to Figs. 5 and 6, are curved on the arc of a circle to receive the cutter dogs 42 which are shaped to fit loosely therein. When said dogs are in inoperative position as shown in Fig. 5 they will be housed entirely within
- 25 the supporting blocks 38 and will not interfere with the movement of the core.

- 30 Each cutter dog is formed with a transverse opening 43 therein somewhat below the central portion thereof and adapted to receive a transverse pin 44. Said pin 44 is fitted at its ends through slots indicated at 45 in the supporting blocks 38 and project into openings in an outer plate 46 which will be understood from Fig. 2.

- 35 The plates 46 are formed to fit about the outer portion of the dog supporting blocks 48, the upper end being reduced slightly in outer diameter to fit within the lower end of the drill collar 20 to which they are secured by screws indicated at 47 in Fig. 3. These plates thus support the transverse pins 44, and when said plates are moved upwardly along with the drill collar, the transverse pins 44 will also be moved as shown in Fig. 6 to force the cutter dogs into a core-engaging position.

- 40 The drill collar is slideable over the upper end of the drill body 10, but it is secured non-rotatably to said drill body by means of keys 50. Said keys are fitted through rec-

tangular openings 51 in the drill collar at a point spaced above the drill head. They may be welded in position as shown at 52 so as to form during operation an integral part of the drill collar. The inner sides of these keys fit within keyways 53 in the outer face of the drill body. As will be seen from Fig. 9 I employ a plurality of these keys, and it is to be understood that as many keys of this character may be employed as is necessary to withstand the driving torque between the drill collar and the drill.

45 I have shown each of the blocks 50 which form the keys just described, with threaded openings 54 therein, which may under ordinary circumstances be closed by threaded plugs. Said plugs may, however, be removed to allow the insertion of a nozzle upon a grease gun, whereby lubricant may be forced into the keyways 53 and the space between the drill collar and the drill body.

50 I contemplate filling the space between the drill collar and the drill body with lubricant, so that when it is desired to move the drill collar longitudinally relative to the drill body, the two parts will not stick together and prevent free movement.

55 It will be seen that the keyways 53 are longer than are the keys 50, so that sufficient longitudinal movement of the drill collar on the drill body may be obtained to provide the necessary relative movement to move the core-engaging dogs as previously described. When this movement takes place, lubricant within the keyways and between the drill collar and the body will be pumped from one end thereof to the other. On the outer side of the drill body on the upper end thereof I form channels 55 to allow the passage of lubricant. These channels will be seen in Fig. 4; the inner collar or sleeve 17 previously described maintains a close fit with the inner side of the drill body, thus tending to prevent the escape of the lubricant to the interior of the drill head by allowing the lubricant to fill the space formed at the upper end of the drill body when said body is moved downwardly. Similar passages 56 are formed between the keyways 53 and the upper ends of the chamber 22 within which the floating packing ring 24 is mounted.

60 The floating ring 24 is adapted to bear against the lubricant to prevent its passage downwardly. The pressure of liquid in the hole outside of the drill will be exerted against the lower end of the floating collar 24, and when the drill is going into the hole the static fluid pressure will gradually increase. If it were not for the floating packing ring, the increased pressure below the packing would tend to force mud past the ring into the lubricant. But with my new ring, the packing may move to exert the well pressure upon the lubricant so that there may be equal pressure on both sides of the packing. Chan-

nels 59 in the said drill body are provided to connect with similar passages 60 in the tubular pins 15, thus allowing the flushing fluid to flow directly against the cutters 31 as is usually desirable.

In the operation of my improved drill, the device will be assembled as shown in Fig. 1, and in thus assembling the device, it is to be understood that the parts may be welded together as previously described. When the drill is in cutting position with the weight of the drill stem resting downwardly upon the drill, the parts will be in the position shown in Fig. 1, and the core-engaging dogs 41 will be withdrawn. The core cut by the drill will pass upwardly into the core barrel 58 in the usual manner, and when it becomes desirable to remove the drill from the hole, an upward pull upon the drill stem will move the drill collar 20 upwardly, thus pulling the core dogs inwardly against the core as shown in Fig. 6. These dogs will be moved into position to break and engage the core by a longitudinal movement sufficient to bring the keys 50 against the upper ends of the keyways 53. The weight of the drill will then be supported upon said keys, and the core will be broken off and moved upwardly with the drill.

By making the core engaging dogs of arcuate shape, they are best adapted to be withdrawn when desired. If the drill stem is moved to advance the dogs and is again set back on the bottom to drill, the dogs can easily move back from under the broken core without sticking due to their shape and the path in which they can move.

By constructing the drill head and securing it to the drill body in the manner described, I am enabled to mount the core engaging dogs close to the bottom of the hole so that the core may be broken off near the lower end thereof, without material loss of the sample taken.

A further advantage lies in the manner in which the flushing fluid may be carried downwardly into effective engagement with the rolling cutters. The manner in which the lubricant is employed to prevent the sticking of the drill collar to the drill body is also a feature of advantage.

What I claim as new is:

1. In a core drill, a cutter head, cutter supports thereon, a drill body, means to secure said head to said body, cutters in said supports, core engaging means comprising arcuate dogs housed slidably in arcuate recesses in said body, a drill collar telescoping over said body, means connecting said drill collar and said body but allowing a limited relative longitudinal movement between them, and means on said collar connected with said dogs to move said dogs and advance said dogs to core engaging position when said drill collar is moved upwardly.

2. In combination, a drill head, cutters thereon, a drill body, means securing said head to said body, core catcher blocks set rigidly between said head and said body, said blocks having arcuate passages therethrough dogs slideable longitudinally in said passages, a drill collar on said body, and means on said collar engaging said dogs to move said dogs to and from core engaging position by the relative movement of said drill collar. 70

3. In combination, a drill head, cutters thereon, a drill body, means securing said head to said body, core catcher blocks set rigidly between said head and said body, said blocks having arcuate passages therethrough, dogs slideable longitudinally in said passages, a drill collar on said body, extensions on said collar, transverse pins on said extensions engaging through openings in said dogs and adapted to slide said dogs in said passages through movement of said collar. 80

4. In a combination, a drill head, cutters thereon, a drill body, means securing said head to said body, core catcher blocks set rigidly between said head and said body, said blocks having arcuate passages therethrough, dogs slideable longitudinally in said passages, a drill collar on said body, downward extensions on said collar, means on said extensions engaging said dogs, whereby an upward pull on said collar will advance said dogs, and means to limit the movement of said collar relative to said body. 90

5. In a core drill, a tubular body, a head thereon, cutter supports on said head engaging said body, cutters on said supports, housings for core engaging dogs mounted on said head between said supports, dogs therein, a drill collar on said body, and means on said collar engaging said dogs to move them relative to said housings. 100

6. In a core drill, a tubular body, a head thereon, cutter supports on said head engaging said body, cutters on said supports, housings for core engaging dogs mounted on said head between said supports, there being arcuate openings in said housings, dogs slideable therein, a drill collar on said body, and extensions on said collar engaging said dogs 110 to move said dogs in said openings.

7. In a core drill, a tubular body, a comparatively short ring-shaped head, cutter supports mounted on said head and engaging said body, means on said body slideable into engagement with said supports, housings between said supports on said head, arcuate dogs slideable in openings in said housings, a drill collar on said body, and means on said collar responsive to a relative upward movement of said collar to move said dogs. 120

8. In a core drill, a tubular body, a comparatively short ring-shaped head, cutter supports mounted on said head and engaging said body, means on said body slideable into 130

engagement with said supports, housings between said supports on said head, arcuate dogs slidable in openings in said housings, a drill collar on said body, and downward extensions on said collar engaging with said dogs whereby a longitudinal movement of said collar on said body will slide said dogs in said openings.

9. A core drill including a tubular body, 10 a head secured thereto, cutters on said head, a drill collar telescoping over said body and having a limited longitudinal movement relative thereto, core engaging dogs adapted to be moved by said collar, and a floating packing ring between said collar and said body to enclose lubricant within said collar.

10. A core drill including a tubular body, a head secured thereto, cutters on said head, a drill collar telescoping over said body and having a limited longitudinal movement relative thereto, core engaging dogs adapted to be moved by said collar, keys on said collar engaging within keyways in said body, and a floating packing ring fitting between said body and said collar and serving to confine lubricant between said collar and said body within said keyways.

11. A core drill including a tubular body, 30 a head secured thereto, cutters on said head, a drill collar telescoping over said body and having a limited longitudinal movement relative thereto, core engaging dogs adapted to be moved by said collar, keys on said collar extending into keyways in said body, lubricant circulating passages between said collar and body, means to pack one end of said passages and a floating packing ring movable between said collar and body at the other end to allow movement of lubricant between said packing means and said ring.

12. In a core drill, a tubular body, a head thereon, cutters on said head, core catcher housing associated with said body having arcuate chambers therein opening toward 45 the inner side of said body, arcuate dogs fitting freely in said chambers and slidable therein, a drill collar having a limited sliding movement relative to said body, and means on said collar engaging said dogs and adapted to slide them longitudinally in said openings when said collar is moved relative to said body.

In testimony whereof, I hereunto affix my signature, this the 18 day of March, A. D. 55 1931.

LOUIS H. WELLENSIEK.
